US00D531981S

(12) **United States Design Patent** (10) Patent No.: **US D531,981 S**
Akita (45) Date of Patent: **** Nov. 14, 2006**

(54) **RADIOCOMMUNICATION EQUIPMENT**

(75) Inventor: **Yasushi Akita**, Osaka (JP)

(73) Assignee: **Icom Incorporated**, Osaka (JP)

(**) Term: **14 Years**

(21) Appl. No.: **29/236,144**

(22) Filed: **Aug. 12, 2005**

(30) **Foreign Application Priority Data**

Apr. 19, 2005 (JP) 2005-11626

(51) LOC (8) Cl. **14-03**

(52) U.S. Cl. **D14/188; D14/217**

(58) **Field of Classification Search** D14/188, D14/137, 160, 168, 217, 265, 192-197, 257, D14/258, 299; 455/344-351; 369/1, 6-12

See application file for complete search history.

(57) **CLAIM**

The ornamental design for radiocommunication equipment, as shown and described.

DESCRIPTION

FIG. 1 is a front view of the radiocommunication equipment according to the present invention.

FIG. 2 is a perspective view of the radiocommunication equipment according to the present invention as seen from the front, top and right side thereof.

FIG. 3 is a top view of the radiocommunication equipment according to the present invention; and,

FIG. 4 is a bottom view of the radiocommunication equipment according to the present invention.

The broken lines are for illustrative purposes only and form no part of the claimed design.

1 Claim, 4 Drawing Sheets

FIG. 1

FIG. 2

FIG. 3

FIG. 4
